RAIL BOND TERMINAL

Carl E. Stolnacke and Ernest J. Sabol, Worcester,
Mass., assignors to The American Steel and
Wire Company of New Jersey, a corporation of
New Jersey

Application December 14, 1937, Serial No. 179,750

3 Claims. (Cl. 173—280)

This invention relates to rail bond terminals of the type applied to a relatively small diameterd, shallow, bottomed recess formed in the side of the head of a rail.

Generally speaking, a terminal constructed according to this invention includes the combination of a head to which the necessary bond conductor may be fixed, a longitudinally bifurcated stud extending from this head for insertion in a recess of the character mentioned and a wedge for longitudinal insertion between the parts of this bifurcated stud with its small end pointing toward the aforementioned head and having a taper permitting its large end to project beyond the end of the bifurcated stud without material expansion of the latter. This large end is adapted to contact the bottom of the rail recess when the stud is partially inserted in the same, and to expand the stud by reason of the latter's bifurcated character upon the stud being forced further inward.

Terminals embodying the above principle, along with certain modifications, are illustrated by the accompanying drawings, in which:

Figure 1 is an installed bond of the type with which the present invention is concerned and embodying the features of the same.

Figures 2 and 3 are sections, both taken from the lines II—II in Figure 1, Figure 2 showing the terminal about to be installed and Figure 3 showing the installation.

Figure 4 illustrates a modification of the terminal shown by the first three figures.

Figures 5 and 6 are sections similar to Figures 2 and 3 but illustrate a second example.

Figure 7 shows this second example disassembled in elevation.

Figure 8 is a section taken from the line VIII—VIII in Figure 7.

Figure 9 is a modification of one of the elements shown by Figure 7.

Figure 10 is a view similar to Figure 7, but showing a modification of the second example.

Figure 11 is a sectional view showing a second modification of the second example.

Figure 12 is a section showing the installation of the terminal illustrated by Figure 11.

To more clearly illustrate the use of the invention, reference may be made to Figure 1, which shows two rail ends 1 bonded by a short conductor 2 having terminals 3 of the character with which the invention is concerned. Figure 2 shows the terminal head 4 from which the longitudinally bifurcated stud 5 extends and the wedge 6 which is inserted between the parts of

the stud, with its small end pointing toward the head 4, this wedge having a taper permitting its large end to project beyond the end of the stud without material expansion of the latter. Since the stud is not expanded it can be easily slipped into the position shown by Figure 2. The next figure, numbered 3, shows the terminal after a hammer 7 has applied force to the outer surface of the head 4 to cause the wedge 6 to perform its function. It will be noted that the head 4 is shown as having a cylindrical side and that the surface of the head 4 opposite the stud 5 is centrally raised, as at 8, so as to flatten (as it has done in the case of Figure 3) without materially deforming this cylindrical side. The wedge functions primarily as a wedge, although its end may plastically deform to some extent, as illustrated.

A modification of this first example is shown by Figure 4, this modification being characterized by a stud 9 which is not completely bifurcated, and by the use of a wedge 10 which is somewhat shorter than the wedge 6, although both wedges have widths not greater than the diameter of the studs so as to prevent their projecting laterally when in use.

The terminal constituting the second example, shown by Figures 5 through 8, embodies a head 11 from which a longitudinally bifurcated stud 12 extends, it being in this respect similar to the first example. However, the wedge 13 used in this case is pin-like in that it is of circular cross-section, as contrasted to having the flat sides of the wedges previously shown. To accommodate this wedge 13, the two parts of the stud 12 are oppositely grooved, as at 14, to provide a longitudinal passage for receiving the pin-like wedge, the head 11 being provided internally with a recess 15 of sufficient extent to permit the insertion of the wedge 13 to an extent effecting proper expansion of the stud 12. Figures 5 and 6 show this second example in the two stages of its installation.

The first modification of this second example is illustrated by Figure 9, wherein a pin 16 having wings 17 fitting between the parts of the stud 12 is substituted for the wedge 13. These wings 17 may be tapered to provide auxiliary wedges, if desired, and in all cases function as guiding elements for the pin-like wedge.

Figure 10 illustrates a second modification of this second example, the same parts being used as shown by Figure 7 except that the passage 15 is replaced by a passage 15a that is shallower than the other so that when the pin 13 has par-

tially performed its function as a wedge it strikes the end of this passage 18* and from then on functions as a plastically expanding plug throughout its length. This requires the pin to be made of metal that is sufficiently rigid to function as a wedge but which is sufficiently malleable to flow when installed by compression greater than that required to cause the just mentioned function, whereby it may ultimately perform its second function.

In the case of the third example, shown by Figures 11 and 12, the same results may be secured as follow from the use of the second modification of the second example except that more control is provided the workman. This third example has a head 18 and a bifurcated stud 19, the two parts of the latter being grooved, as at 20, to provide a passage for a pin-like wedge 21, the distinguishing feature being that the recess 18* previously mentioned is substituted by a bore 22 which extends completely from the passage 20 to the outside surface of the head, where it opens. Then the wedge 21 is longer, it having a length exceeding the total length of the terminal, so that in the case of this third example, the wedge 21 performs its wedge function until the head 18 strikes the side of the rail head surrounding the recess, this bringing the small end of the wedge 21 beyond the outer surface of the head 18, due to its large end contacting the bottom of the recess. Thus, the small end of the wedge is accessible and can be struck with the hammer so as to cause its plastic deformation. If the hammer is used against the center of the head 18 at the opening of the bond 22 at this time, the wedge will automatically function as a wedge and as a plastically expanded plug.

We claim:

1. A rail bond terminal including the combination of a head, a longitudinally bifurcated stud extending from said head for insertion in a bottomed rail recess and a wedge for longitudinal insertion between the parts of said stud with its small end pointing toward said head and having a taper permitting its large end to project beyond the end of said stud without material expansion of the latter, said large end being adapted to contact the bottom of said rail recess when said stud is partially inserted therein and expand said stud upon the latter being forced further inwardly, said wedge being pin-like and said parts of said stud being oppositely grooved to provide a longitudinal passage for said wedge, the length of said passage being less than the length of said wedge so that when the small end of the latter

reaches the end of said passage it functions as a plastically expanding plug, said wedge being made of material sufficiently malleable to flow when stressed by compression greater than that required to cause it to function as a wedge.

2. A rail bond terminal including the combination of a head, a longitudinally bifurcated stud extending from said head for insertion in a bottomed rail recess and a wedge for longitudinal insertion between the parts of said stud with its small end pointing toward said head and having a taper permitting its large end to project beyond the end of said stud without material expansion of the latter, said large end being adapted to contact the bottom of said rail recess when said stud is partially inserted therein and expand said stud upon the latter being forced further inwardly, said wedge being pin-like and said parts of said stud being oppositely grooved to provide a longitudinal passage for said wedge, and said head having a bore communicating with said passage, said pin-like wedge being sufficiently long to project through said bore beyond the outer surface of said head when the end of said stud is forced toward contact with the bottom of said recess, whereby force can be applied to said wedge to cause its plastic expansion, said wedge being made of material sufficiently malleable to flow when stressed by compression greater than that required to cause it to function as a wedge.

3. A rail bond terminal including the combination of a head, a longitudinally bifurcated stud extending from said head for insertion in a bottomed rail recess and a wedge for longitudinal insertion between the parts of said stud with its small end pointing toward said head and having a taper permitting its large end to project beyond the end of said stud without material expansion of the latter, said large end being adapted to contact the bottom of said rail recess when said stud is partially inserted therein and expand said stud upon the latter being forced further inwardly, said combination further including means for effecting the transfer of at least a portion of the force applied to force said stud further inwardly, directly to the small end of said wedge and longitudinally of the latter prior to said stud being forced to its final position, said wedge being made of material sufficiently malleable to flow when stressed longitudinally by said transfer of said force to an extent greater than that required to cause it to function primarily as a wedge.
